UNITED STATES PATENT OFFICE.

LEVI M. DEVORE, OF FREEPORT, ILLINOIS.

DESIGN FOR A COVERING-PLATE.

SPECIFICATION forming part of Design No. 27,661, dated September 21, 1897.

Application filed August 6, 1897. Serial No. 647,380. Term of patent 7 years.

To all whom it may concern:

Be it known that I, LEVI M. DEVORE, a citizen of the United States of America, residing at Freeport, in the county of Stephenson and 5 State of Illinois, have invented a new and original Design for an Ornamental Covering-Plate for the Fork Ends of Bicycles, of which the following is a specification.

The design which is the subject of my invention is a new and ornamental as well as 10 useful shape or configuration of a covering intended for use upon the fork ends of bicycles to give the same a neat and pleasing appearance.

15 The invention is illustrated in the drawings presented herewith by means of three figures, of which—

20 Figure 1 is an outside view of one of the plates. Fig. 2 is an inside view; and Fig. 3 is a section in line 3-3 of Fig. 2, looking in the direction of the arrow 2.

The covering here shown consists of a plate

A of substantially uniform thickness containing an elongated opening B and widest at the portion lettered a, from which it tapers to the 25 end a'. Around the outer margin, between the letters a a', is an inturned flange C.

The essential features of my design I consider to be the tapering plate A of substantially even thickness having the inturned 30 flange C.

I claim as new and desire to secure by Letters Patent—

The design for an ornamental covering-plate for the fork ends of bicycles herein 35 shown and described.

In witness whereof I have hereunto set my hand, at Chicago, in the county of Cook and State of Illinois, this 28th day of July, A. D. 1897.

LEVI M. DEVORE.
